UNITED STATES PATENT OFFICE

2,371,482

BERTH

James K. Tully, Evanston, Leif Andersen, Chicago, and Basil E. Jones, Flossmoor, Ill., assignors to The Pullman Company, Chicago, Ill., a corporation of Illinois

Original application July 31, 1940, Serial No. 348,670. Divided and this application March 14, 1941, Serial No. 383,262

5 Claims. (Cl. 105—315)

The overall dimensions of railway passenger cars are definitely limited in order to provide the required clearances to permit trains to pass one another and to clear tunnels, overhead bridges, and other structures along the right-of-way. With these outer limits of the car fixed, the problem of increasing the capacity of the car is extremely difficult, and requires readjustments of the interior arrangement to efficiently utilize every cubic inch of available space for the purpose of accommodating passengers. Any space in a passenger car which is used for purposes other than accommodating passengers is wasted in so far as the revenue earning power of that car is concerned.

Modern day coaches can accommodate anywhere from forty-five to sixty-eight passengers, depending upon the floor plan lay-out of the particular car, whereas a standard Pullman twelve section car having a drawing room at the end can accommodate about twenty-seven. The overall dimensions of both of these types of cars are approximately the same, so that the variation in the number of passengers which can be accommodated in these different types of cars is accounted for by the different floor plan lay-outs in the cars. In the day coach, each passenger is provided with a seat, which, at best, allows him to assume a semi-reclining position in which he may sleep. In a sleeping car, on the other hand, each occupant has a comfortable bed in which he may sleep in a fully reclining position. Obviously, the amount of floor space in a car required for a bed is considerably greater than that needed for a seat, so that the capacity of a sleeping car necessarily is much less than that of a day coach.

One of the principal objects of the present invention is to provide an arrangement of seats and berths which more efficiently utilizes the available space in a car so as to greatly increase the capacity of a sleeping car over and above that of the present cars. This is made possible by an arrangement of berths which provides adequate seating space for the occupants during the daytime with ample leg, arm, and head room and comfortable roomy beds for night time travel. It is intended that this shall be accomplished in a very simple, inexpensive manner so that the porter in charge of the car can quickly convert the berths from day to night use, and vice versa, with a minimum amount of inconvenience to the passengers, and at the same time it is intended to provide the occupants with the maximum

amount of comfort, both during the daytime and at night.

The above constitute some of the principal objects of the present invention, others of which will become apparent from the following description, in which

Fig. 1 is a fragmentary perspective view of a car showing a three and a six passenger room made up for day use and the relationship of the rooms with respect to the car aisle;

Fig. 2 is a fragmentary perspective view of a car corresponding to Fig. 1 with the rooms made up for night use;

Fig. 3 is a longitudinal sectional view through a car showing a three occupant room made up for day use and a six occupant room made up for night use;

Fig. 4 is an exploded perspective view of the convertible sofa forming the lower berth with parts broken away;

Fig. 5 is an enlarged vertical sectional view taken through one of the convertible sofas;

Fig. 6 is a vertical sectional view corresponding to Fig. 5 but showing the arm rest in position for day use and the seat moved to its reclining position;

Fig. 7 is a vertical sectional view through the sofa showing the arm rest in position for day use and a means for fastening the soft back in the daytime position;

Fig. 8 is a vertical sectional view through the convertible sofa taken on the line 8—8 of Fig. 10 and showing the sofa back folded down for night time use;

Fig. 9 is an enlarged vertical sectional view taken through the arm rest on the line 9—9 of Fig. 8;

Fig. 10 is a fragmentary vertical transverse sectional view through the room portion of the car showing in front elevation the convertible sofa in condition for night use, the view being taken on the line 10—10 of Fig. 8;

Fig. 11 is a vertical sectional view taken lengthwise through the convertible sofa back when it is in its lowered position for night time use, the view being taken on the line 11—11 of Fig. 8;

Fig. 12 is an enlarged vertical sectional view taken through a portion of the convertible seat on the line 12—12 of Fig. 8;

Fig. 13 is an enlarged vertical sectional view taken crosswise of the upper and intermediate berths showing in solid lines the relative positions of the upper and intermediate berths when in their daytime position and indicating in

broken lines the intermediate berth in position for night use with a counter-balancing mechanism associated with the intermediate berth;

Fig. 14 is an enlarged detail view of a portion of the upper and intermediate berths taken on the line 14—14 of Fig. 13;

Fig. 15 is a sectional view taken on the line 15—15 of Fig. 13, showing the upper and intermediate berth arrangements when they are in position for night use, portions of the figure being broken away;

Fig. 16 is an enlarged detail view of a portion of the upper and intermediate berths when in their daytime position taken on the line 16—16 of Fig. 13;

Fig. 17 is an enlarged detail view of the wall bracket which supports the intermediate berth in its day position;

Fig. 18 is a side elevational view of the curtains for the upper berth, the view being taken from the inside of the berth and looking at the inner face of the curtains;

Fig. 19 is a side elevational view of the curtains for the intermediate and lower berths, the view being taken from the inside of the berths looking toward the inner face of the curtains;

Fig. 20 is a vertical sectional view taken through the upper and lower curtains in their assembled positions on the berths; and

Fig. 21 is a vertical sectional view through the curtains for the intermediate and lower berths taken on the line 21—21 of Fig. 19.

This application is a division of the co-pending application of Peter Parke, James K. Tully, Leif Andersen, and Basil E. Jones, Ser. No. 348,670, filed July 31, 1940.

A specific embodiment of the present invention is selected for the purpose of disclosure, as required by section 4888 of the Revised Statutes. Many modifications may be made without departing from the scope of the invention.

The berths forming the subject matter of the present invention are shown in connection with a railway sleeping car (Fig. 1) having a floor 51, side walls 52 and 53, and a roof 54. An aisle 55 extends lengthwise to the car adjacent to the side 52, and a plurality of rooms 56 are arranged adjacent to the opposite car side wall 53. Windows 82 are spaced in the wall 53 in a manner to give suitable daylight to each room and to provide clear vision outside the car. The rooms are separated from each other by transverse partitions 84 and from the aisle by a partition 85. Each of the transverse partitions 84 is open, as indicated at 61, over a substantial portion of its area to provide a view throughout the length of the car. As shown, the aisle partition 85 is open, as indicated at 62, over a substantial part of its area. A curtain, generally indicated at 61' in Fig. 1, may be used to close the opening in the transverse partition 61, as can other suitable means, and curtains 585 (Fig. 2) may be used to close each room for the aisle.

Each room is provided with berths arranged in a tier of three with the lower one convertible into a sofa 87 (Fig. 3), the upper berth 88 assuming a stationary position in the upper region of the room, and the intermediate berth 89 foldable to a position adjacent to the underneath face of the upper berth 88, as shown in Fig. 1. The intermediate berth is adapted to assume a horizontal position for use, and is provided with a pan 263 (Fig. 3), which may be secured over the opening in the transverse partition.

As shown in Fig. 1, the room is further pro-

vided with equipment to make the room furnishings complete both for day and night use.

SPECIFIC DETAILS

Convertible sofa

The sofa in each room is arranged to provide three comfortable seats, with or without arm rests, depending upon the requirements of the individual occupant. Each seat may be individually adjusted to an upright or semi-reclining position to suit the needs of the occupant.

The sofa is supported on a frame generally indicated at 116 in Fig. 4, secured to the side wall 53 of the car and to the aisle partition 85 (Fig. 10) by brackets 111. Bosses 242 project down from the frame through holes in the brackets. This frame comprises a pair of spaced parallel beams 118 and 119 (Fig. 4) extending the full length of the sofa connected by a plurality of channel-shaped guide members 120 and an angle end guide member 121, all of which guide members extend crosswise with respect to the two beams 118 and 119. The angle member 121 is used on the end of the sofa frame adjacent to the aisle side, while the channel members are used in intermediate positions and on the car wall side of the sofa frame.

Each of beams 118 and 119 comprises a wooden core 122 bound on its sides by metal channel members 123 and 124. The seat guides 120 and 121 are fastened to the beams 118 and 119, and are so spaced that a seat cushion fits between two adjoining seat guide members.

The upwardly extending sides of the guide members are provided with slots 125 having downwardly extending portions 126 and horizontal portions 127. A seat cushion 128 fits between contiguous sides of adjoining seat guide members 120 and trunnions 129 on the sides of cushions 128 fit in the slots 125 of the guide members.

Directly adjacent to each guide member on the forward beam 118 of the frame 116 is a seat slide 130, which is an angle member extending across the top of beam 118 and bending downwardly against the inner side of the beam. In the top horizontal flange of the seat slide 130 is a slot 131. These seat slides are provided on each side of the seat cushion area between adjoining seat guide members.

At the back of the frame on the rear beam 119 is a seat back catch slide 132 of irregular shape having a horizontal portion 133 extending over the top of beam 119, a downwardly and rearwardly inclining portion 134, and a vertical portion 135. An angle member 136 (Figs. 5 and 6) is fastened to the inner side of the vertical portion 135 of the slide and has a horizontally extending flange 137 engaging the lower face of beam 119 and a vertical flange 137' engaging the inner face of the vertical portion 135 of the seat back catch slide 132.

The cushion 128 is supported on a frame 138 including angular members having a horizontal flange 139 and a vertical flange 140. These angular members extend along the sides and across the back of the cushion. The cushion itself may be of any suitable type with or without springs, but, as shown, it is made of sponge rubber, which inherently has the necessary resilient properties to provide a comfortable seat. This sponge rubber cushion, shown at 141 in Fig. 5, is covered with a suitable upholstering material 141', and the cushion as a unit is carried in the frame 138.

On the bottom face of the horizontal flange 139

of each angle member 140, along each side of the cushion, is a seat slide stop 142 comprising a plate 143 secured to the flange 139 and a downwardly projecting lug 144 having an inclined surface 145. When the seat is in its normal upright position, the cushion 128 is in place between the contiguous sides of the seat guide members 120, or, in the case of the end cushion, between the upright flange of the end seat guide member 121 and the contiguous flange of intermediate guide member 120.

Referring to Fig. 5, the seat is supported on the seat slides 130 underneath the front end of the cushion and on the rear beam 119 of the sofa frame. The seat slide stops 142 assume a position directly behind the seat slide 130 in the space between the two beams 118 and 119.

When the seat is moved to the semi-reclining position shown in Fig. 6, the seat cushion 128 is pulled forward, during which time the lug 144 on each seat slide stop 142 engages its corresponding seat slide 130. As the cushion is moved forward, the inclined surface 145 of lug 144 moves along the seat slide 130, raising the forward edge of the cushion. As the cushion is pulled further forward, the lug moves across the top surface of the seat slide 130 until it fits into notch 131 in this surface. The seat cushion is thus moved to the semi-reclining position of the seat. An angle grasp 147 is secured to the underneath face of the seat cushion 128 directly adjacent to the front edge thereof, and this grasp provides means for manipulating the seat cushion.

Along the back edge of the seat cushion 128 is a seat back catch 148, hinged at 149 to the upwardly extending flange 140 of the cushion frame 138. This seat back catch has a heel portion 151, which engages the vertical, inclined, and horizontal upper surfaces of the seat back catch slide 132 (Figs. 5 and 6) during the movement of the seat cushion from the normal position shown in Fig. 5 to the semi-reclining position shown in Fig. 6.

When the seat is in its normal position, the seat back catch is substantially horizontal, as shown in Fig. 5, with the heel 151 engaging the vertical surface of the seat back catch slide 132. As the cushion 128 is moved forward, the heel 151 rides up the inclined surface 134, causing the seat back catch to rotate in a counter-clockwise direction about the pivot point of hinge 149, thereby raising the seat back catch. When the seat cushion 128 assumes the semi-reclining position shown in Fig. 6, the heel 151 of the seat back catch is supported on the horizontal surface 133 of the slide 132, and the seat back catch thereby assumes a substantially vertical position (shown in Fig. 6). Extending outwardly from the end of the seat back catch is an arm 152.

Referring to Figs. 5 and 6, when the seat cushion 128 is being adjusted from the upright position to the inclined position, the trunnion 129 moves from the rear of slot 125, as shown in Fig. 5, to the forward end of the slot, as shown in Fig. 6. The extremities of the slot 125 limit the movement of the seat cushion 128. To entirely remove the cushion, the trunnion is moved to the rear of the slot and then raised through the vertical portion 126 of the slot. A plate 159 (Fig. 4) is secured to each end of block 166 and blocks the opening at the top of slot 125. This plate must be removed before the seat cushion can be removed.

The channel-shaped seat guide members 120 serve as casings into which arm rests 168 are

folded (see Fig. 4). In each of these guide members 120 is a channel-shaped arm rest support bracket 160 having a rear flange 161 and two side flanges 162 and 163 (Fig. 4). Extending upwardly from the side flanges are projecting arms 164 and 165. The arm rest support bracket is spaced from the end of the seat guide member 120, and, as best shown in Fig. 8, a block 166 is inserted between the support and the end of seat guide member 120. This block is upholstered at 167 (Fig. 8) in any suitable manner.

The arm rest 168 (Fig. 4) fits between the upwardly extending flanges of the channel guide member 120 and comprises back, intermediate, and front members 175, 176 and 169, respectively. The back and intermediate members 175 and 176 are hinged together at 172 (Fig. 8), and the intermediate and front members 176 and 169 are hinged together at 174.

The intermediate member 176 serves as the arm support when the arm rest is in its raised position, the back and front members 175 and 169, respectively, supporting the intermediate member in its raised position. The back member 175 serves to close the space between the seat cushions directly in back of the intermediate arm rest member 176 when the arm rest is folded into the seat guide member 120. The front member 169 folds back underneath the intermediate member when the arm rest is lowered into the guide 120.

The forward member 169 comprises a plate 173, to the outer face of which is secured a block 173'. Suitable upholstering material covers this block.

The free end of the front plate 173 is provided with a flange 178 extending beyond the block 173' at an angle with respect to the plane of the plate 173.

The intermediate arm rest support member 176 comprises a base 193 (Fig. 8) on which is mounted an irregularly shaped supporting member 194. Sponge rubber 195 or other suitable cushion material covers the supporting member 194.

The back member 175 of the arm rest 168 comprises a supporting block 196 on which is secured a cushion 197 of rubber or the like.

Suitable upholstering material indicated at 177 covers the back and intermediate members.

Referring again to Fig. 4, adjacent to the end of the frame along the front edge of beam 118 of the seat frame and directly below the channel-shaped seat guide member 120 is an end arm rest support bracket 179. This bracket is an angle member having a front flange 180 and a side flange 181, the latter of which is secured to the end of beam 118. The front flange of the bracket has an outwardly offset portion 180' spaced from the beam 118 across the area directly below the seat guide member 120, and is secured to the forward flange of beam 118 along the flange 182.

Directly below the intermediate channel-shaped seat guide members 120 are intermediate arm rest fastening brackets 183 having an intermediate outwardly offset portion 184 spaced from the forward edge of beam 118 directly below the seat guide member 120, and flanges 185 and 168 extending beyond the ends of the intermediate portions 184 and secured to the forward edge of beam 118.

As best shown in Fig. 7, the arm rest 168 is provided with trunnions 187 on the opposite sides of the back member 175, which are journaled in slots 188 in the upper ends of projections 164 and 165 on the arm rest support bracket 160. When the arm rest is in position for use, it is raised out

of the seat guide member 120 with the intermediate arm rest cushion member 176 spaced in horizontal relationship above the seat and the back and front members 175 and 173, respectively, extending substantially vertically downward from the intermediate member. The projecting flange 178 on the end of plate 173 is inserted in the opening in bracket 179 (in the case of the end arm rest, or in bracket 183 in the case of an intermediate arm rest support).

As best shown in Figs. 4 and 7, a slot 189 is placed in flange 178 of the arm rest 168, and, when the arm rest is in position for use, a dead-bolt 190 (Fig. 7) is moved forward and inserted in slot 189 to lock the arm rest in position.

The arm rest 168 is lowered into the seat guide member 120 by first unlocking the dead-bolt 190 and raising the flange 178 of the plate 173 out of the arm rest support bracket. Then, as shown in Fig. 8, the plate 173 is folded under the end and intermediate sections 175 and 176 of the arm rest 168, and the assembly is lowered into the seat guide member 120.

The forward edge of the back member 175 of the arm rest 168 is inclined at 191, and the rear end of the intermediate member 176 is similarly inclined at 192, so that when the arm rest is in place in the seat guide member 120 these two inclined surfaces become complementary to each other, so that there is only a slight crack between the intermediate and the back members 176 and 175, respectively.

When the arm rest is not in use and is folded into the seat guide member 120, the top surface of both the intermediate and the back members 176 and 175, respectively, are flush with the seat cushion, and the front edge of the intermediate member 176 is flush with the front edge of the seat cushion, so that, in effect, when in its collapsed position, the arm rest forms a part of the seat cushion.

The sofa back is best shown in Figs. 4-10, inclusive, and includes a lower berth member 198 to which is hinged each seat back cushion 199 by means of a hinge 200. Between adjoining seat back cushions is a spacer 566 supported on the lower berth member 198 by a bracket 567 and an angle bar 568 at the opposite ends, respectively, of the spacer. The lower berth member has trunnion brackets 201 and 202 along the opposite sides thereof, each of which carries a trunnion 203. To the car side wall 53 and the aisle partition 85 are secured pivot brackets 204 (Figs. 7 and 11), in which the trunnions 203 are journaled. In this manner, the lower berth member or sofa back 198 is pivoted about a horizontal axis so that it can assume an upright position shown in Fig. 5, or it can be rotated to a horizontal position shown in Fig. 8.

The structure of the berth member 198 is best shown in Figs. 4 and 5, and includes a frame 205 having angle members 206-209, inclusive, each having a horizontal flange 210 and a vertical flange 211. To the other inner faces of these angle members are secured irregularly shaped angle members 212 having flanges which engage the inner surface of the flanges of the corresponding angle members 206-209, inclusive. A filler 213 is inserted between the irregularly shaped angle members 212 and each of the corresponding angle members 206-209, inclusive. To the upper edge of the flanges 211 of each angle member is secured a wooden member 214, which serves as one side of the lower berth. To the inner face of each side is secured a plate 233 (Fig. 7). Across

the upper or front edge of the frame 198, the side 214 is of lesser height than in the case of the ends and back edge of the frame, and a rubber padding 215 is mounted on the top of the wooden member 214, so as to provide a cushion along this edge of the frame. The bottom of the frame is closed by canvas 216 (Fig. 7), reinforced along its edges at 217 and secured to the inner face of the lower flanges of the angle members 206-209, inclusive.

10 As best shown in Fig. 5, the seat back cushion 199 is hinged to the inner flange 210 of the angle member 206, and this seat cushion, pivoting about the hinge 200, may be moved away at the bottom from the lower berth frame 198, assuming the 15 position shown in Fig. 6. Straps 218 limit the amount of this movement.

The seat back cushion is made up of framing members 219 and 220 at the top and bottom, respectively (Fig. 5), and 221 and 222 (Fig. 11) 20 along the sides of the seat back.

A frame made up of angle members 223 is secured to the framing members 219-222, inclusive. To this frame is secured a sheet 224 (Fig. 5), which completes the frame for the seat back.

25 To the frame is secured sponge rubber 225, or other suitable resilient material, to give the necessary cushioning to the seat, and upholstering 226 may be used to cover the rubber.

Extending downwardly from the lower edge of 30 the seat back is a bracket 227, which projects below the seat back at 228. To the inner face of the bracket is attached a bumper 229, which is covered by a bumper shield 230.

A strap retainer 231 (Fig. 6) is secured to the 35 bottom face of the framing member 220, and a second strap retainer 232 secures the other end of the strap to the lower edge of the lower berth frame.

When the seat is in its upright position, the 40 seat cushion 128 and the back 199 assume the position shown in Fig. 5, with the seat back catch 148 substantially horizontal. As the seat cushion 128 is moved forward, as previously described, to assume the semi-reclining position, the seat back 45 catch rotates counter-clockwise about the hinge 149, and the arm 152 of the catch engages the bracket 228 extending downwardly from the lower edge of the seat back 199. As the forward movement of the seat cushion 128 proceeds, this arm 50 pulls the lower edge of the seat back 199 forward, rotating the seat back about its hinge 200. When the seat has been moved to its semi-reclining position shown in Fig. 6, the seat back catch 148 assumes a vertical position, and the arm 152 on the 55 end thereof supports the lower edge of the seat back 199 away from the berth frame 198, the straps 218 limiting the degree of movement of the seat back 199.

When the sofa back, which includes the lower 60 berth frame 198 and the seat back 199, is in its daytime position, it is held against the room partition 84 (Fig. 7) by a latch 235 pivoted to a latch case 236, the latter of which is secured to the room partition 84. Latch 235 engages a keeper 235' 65 situated on the upper edge of the berth frame adjacent to each end thereof. When the sofa back is rotated to the horizontal position shown in Fig. 8, it forms a lower berth 239. A mattress 237 is permanently held in the lower berth frame 198 by straps 238. Referring to Fig. 10, supporting members 241, attached to the ends of the lower berth 239 adjacent to the forward edge thereof, rest on brackets 240. Brackets 240 are fastened to the car side wall 53 and the aisle partition 85, respectively.

Berth structure and operation

The berths are so arranged that they may be fully made up with the proper bedding. Thus, the porter is not required to make up beds at night when he is converting the car into a sleeper for night use. Much time is thereby saved, and the porter merely is required to assemble the berths for night use.

Upper berth structure

The upper berth 88 (Figs. 14-16, inclusive) is permanently fixed in place and rests on angle brackets 244 attached to the car side wall 53 and aisle partition 85. Angle brackets 245 are positioned at the ends of the berth, one flange 246 of each of which is secured to the berth while the other flange 247 rests on the angle bracket 244.

The upper berth comprises a rectangular frame made up of upwardly opening angle members 248 and a canvas sheet 249 forms the bottom of the berth and is secured to the horizontal flanges of the angle members 248. The upright flanges 250 of the angle members 248 form the sides of the berth frame, and a sponge rubber mattress 251, or some other suitable type of mattress, is permanently held in place in the berth frame.

Referring to Figs. 1 and 2, the relative position of the upper berth with respect to the car walls is shown, and the space between the top of the mattress and the car roof is ample to provide maximum comfort to the occupant.

As best shown in Fig. 16, across the front edge of the upper berth extends a curtain rod 252 having an upper rung 253 and a lower rung 254 extending the full length of the berth, from which the lower and intermediate berth curtains are suspended.

Intermediate berth structure

The intermediate berth 89 (Fig. 15) is made up of an intermediate berth pan 263 comprising a bottom sheet 264 having upright sides 265 and front and back upright members 266 and 266', respectively (Fig. 13).

Referring to Fig. 15, the berth pan is pivoted to the car side wall 53 and the aisle partition 85 about pivot points 267, supported on the car side wall 53 and the aisle partition 85, respectively. When in its closed daytime position, the berth pan 263 is held in a substantially horizontal position directly below the upper berth, as shown in Fig. 13, by a bracket member 268 on each end of the berth pan.

Referring particularly to Fig. 17, each bracket 268 comprises a bracket casing 269 which fits into a well in the wall and has a peripheral flange 270, through which the casing is secured to the wall. Extending outwardly from the inner face of the casing 269 is a lug 271 having an opening 272 adjacent to its outer edge. The bracket 268 is pivoted to the casing 269 at 273 about a vertical axis, so that this bracket may be swung about the pivot point into the closed position in which the outer surface 274 lies flush with the outer surface of the peripheral flange 270. An arm 275 is pivoted to the bracket 268 on the inside thereof about a vertical axis 276. The arm 275 extends inwardly into the casing 269 and through the opening 272 in lug 271. A coil spring 277 surrounds the arm 275 and is held between the lug 271 and a shoulder 278 on the arm 275.

When the bracket 268 is in its open position, as shown in Fig. 17, the spring 277 is compressed between the shoulder 278 and the lug 271 to urge the bracket in its open position. When closing

the bracket 268, force is applied to overcome the force of spring 277 and move the bracket in a counter-clockwise direction about pivot point 273. During the closing of this bracket, pivot point 5 276 rotates about pivot point 273 until it reaches dead center in line with the pivot point 273 and the opening 272 in lug 271, at which time the effect of the spring 277 in maintaining the bracket 268 in open position is overcome. Upon further 10 closing of the bracket 268, pivot point 276 moves to a point inwardly of dead center position, so as to apply counter-clockwise force on the bracket 268 to urge the bracket in the closed position. Thus, the effect of the spring when the bracket 15 268 closely approaches the closed position is to snap the bracket to and hold it in the closed position.

An intermediate berth 279 closes into and is held by the intermediate berth pan 263, and comprises a frame, generally indicated at 280 (Figs. 13-15, inclusive), comprising angle members 280 secured together in the form of a rectangle with a sheet of canvas 281 closing the bottom of the rectangular frame and secured to the angle members 280. The intermediate berth frame is pivoted to the side walls 265 of the intermediate berth pan 263 at 282 and 283 adjacent to the front edge 266 of the berth pan. Brackets 284 and 285 are secured to the opposite sides 280 of the berth pan, and each has a centrally inwardly offset portion 286 to which the intermediate berth is journaled. As best shown in Fig. 13, a chain 287 at each end of the intermediate berth is secured to the outer end of the intermediate berth at one end and to the outer end of the stationary upper berth 88 to suspend the outer edge of the intermediate berth from the upper berth. A mattress 288 is held in the intermediate berth frame.

In Fig. 13, the intermediate berth is shown in its closed position housed in the intermediate berth pan 263 held against the underneath face of the upper berth by brackets 268. A plate 289 is fastened to the underneath face 264 of the intermediate berth pan adjacent to the bracket 268 at each end of the berth. To lower the intermediate berth, an upward force is applied under the front edge of the berth pan, and the brackets 268 on both sides of the berth are snapped to their closed position. The berth pan is then allowed to rotate downwardly in a counter-clockwise direction about its pivot points 267 and 268 (Fig. 15) until it assumes the vertical position shown in dotted lines at 290 in Fig. 13. Latches 291 engaging catches 292 on the outer edge of the berth pan hold the intermediate berth pan in this vertical position. The intermediate berth is held in the intermediate berth pan by a latch 259 (Fig. 14) fitting into a slot 258 in each side of the intermediate berth pan. When lowering the intermediate berth, it is first unlatched; then rotated about its pivot points 267 and 268 (Fig. 15) until it assumes the horizontal position shown in dotted lines 293 in Fig. 13, the chain 287 supporting the outer edge of the berth.

The intermediate berth pan with the weight of the intermediate berth is counterbalanced at each end by a coil spring 294 (Fig. 13), which extends at right angles to the berth and is fastened at one end to a bracket 295, secured to a wall of the room. A chain 296 is attached to the opposite end 297 of spring 294 and passes over a sprocket wheel 298 journaled to the room wall, and then downwardly to a chain clevis 299 pivoted to one of the side walls 265 of the intermediate berth pan at 300. A counter-balancing spring 294 is

provided at each end of the intermediate berth pan, so that two of such springs serve to counter-balance the weight of the intermediate berth.

A housing 301 (Figs. 13 and 16) enclose the counter-balancing springs for intermediate berths on opposite sides of the room (in the case of the six-occupant room), in which case spring 294 (Fig. 16) serves to counter-balance half of the weight of one of the intermediate berths, and spring 294' counter-balances half of the weight of the intermediate berth on the other side of the room. The spring casing 301 is secured to the car wall by screws 302. In this manner, the bulk of the counter-balancing equipment is completely enclosed.

The springs 294 are so arranged that the weight of the intermediate berth overcomes the spring action when the berth assumes a position midway between the closed and open position, so that when lowering the intermediate berth its weight permits it to drop to a position substantially at an angle of 45 degrees with respect to the horizontal, and force is required to place the berth in the vertical position 290 against the room partition 84.

The rod 243 is fastened to the front edge of the intermediate berth, and the curtain is secured thereto.

In order to simulate as nearly as possible the open car, the opening 61 (Fig. 1) in the partition 84 separating adjoining rooms should be as large as possible and extend down approximately to the tops of the sofa seat backs.

Referring to Fig. 5, a panel 303 is hinged to each partition 84 directly behind each sofa back by means of hinges 304 secured to brackets 305, which in turn are fastened to the partitions 84. Each panel 303 is provided with a strip of rubber 306 across the top edge of the panel on the outer face thereof when the panel is in its raised position against the partition 84, so that when the intermediate berth pan 263 is lowered as shown in Fig. 3, the rubber seals the crack between the panel 303 and the lower edge of the berth pan.

The strip of rubber 306 also serves as a bumper between the panel 303 and the partition 84 when the partition is in its lowered position, thereby reducing vibrations which may otherwise be present.

Vertical strips of rubber 307 and 307' may extend along the vertical edges of the panel on the inner side thereof when it is in its raised position, thereby sealing the panel against the partition 84 on each side of the cut-away portion 61 of the partition.

Headboard panel

A headboard panel 308 (Fig. 2) fits at the end of the berth on the outside to fill out the aisle partition when the berths are made up for night use. A pair of fingers 310 (Fig. 3) are secured to the panel at the bottom and project below the lower edge thereof, and a pair of brackets 311 are secured to the aisle partition on the room side thereof and directly below an arm cushion 312 at the aisle end of the sofa.

The projecting fingers 310 are inserted in the brackets 311 when the headboard is placed in position at the end of the sofa, and a finger 313 along the side of the panel is inserted in a bracket 314 located on the inner face of the aisle partition (Fig. 3). With the panel in place, a bolt 315, secured to the panel by brackets 315', is raised into the keeper 316 on the aisle partition, locking the headboard in place.

Berth operation

The operation of the berths is as follows:

Assuming that the berths are in their position for daytime use, as shown in Fig. 1, and one or more seats are in their semi-reclining position, the first operation which the porter performs to convert the equipment into berths for night use is to place the adjustable seats in their normal upright position shown in Fig. 5. The headboard 308 is first inserted in place at the end of the sofa in the aisle partition. The sofa back 199 is then unlatched at the top at 235 (Fig. 7) and rotated in a counter-clockwise direction about its pivot 203 (Fig. 4) until it comes to rest on the wall brackets 240 (Fig. 10). Next, the hinged panel 303 (Fig. 7) is moved up to close the lower part of the opening 61 (Fig. 3), and then the intermediate berth pan 263 (Fig. 13) is unlatched by rotating the brackets 268 into their wall recesses. The intermediate berth pan is then lowered to the vertical position shown in dotted lines 290 in Fig. 13 and latched in place. The intermediate berth 293 is then unlatched at 259 and rotated down to the horizontal position shown in dotted lines 293. Inasmuch as the upper berth is stationary, the three berths are now in position for use.

Berth curtains

Referring to Figs. 18-21, inclusive, the berths are provided with upper and lower curtains 595 and 596, respectively.

Each upper curtain 595 encloses an upper berth, and is made up of two segments 597 and 598. Referring to Fig. 18, a rod 599 is attached to the ceiling of the car and extends lengthwise of the upper berth. Adjacent to the top edges of segments 597 and 598 of the upper berth curtain 595 is a plurality of hooks 600, which support the upper curtain on rod 599. The upper edge of the curtain is reinforced at 601. The curtain segment 598 is cut out at 608 (Fig. 18) to fit the curtain around the exhaust air duct 584, and a hook 609 hooks onto an eyelet (not shown) fastened onto the car wall to support the end of the curtain segment.

As best shown in Fig. 20, the upper berth curtain 595 extends below the upper berth 88. Adjacent to the lower edge of the upper berth curtain 595 is a strap 602 for each of the segments 597 and 598. Each of these straps 602 extends substantially the full width of its corresponding curtain segment, and is stitched or otherwise secured to the curtain segment at 603, and buttons 604 are spaced across each strap directly below the line of stitching. Buttonholes 605 are placed along the lower edge of each strap 602, and, when each segment is in place suspended from the rod 599, the strap 602 is wrapped around the upper rung 253 of the rod 252, and then buttoned, as best shown at 606 in Fig. 20. Thus, the upper berth curtain segments serve as safety belts to prevent the occupant of the upper berth from rolling out or being tossed out of the upper berth. The segments 597 and 598 come together substantially midway between the ends of the berth and are buttoned together at 607 (Fig. 18).

The intermediate curtain 596 comprises segments 611 and 612, across the top of each of which is a strap 613, secured to the curtain segment at 614, which wraps around the lower rod or rung 254 and buttons at 615 (Fig. 20). Each of segments 611 and 612 extends from the lower rung or rod 254 to somewhat below the lower berth 198. The segments 611 and 612 come to

gether along a vertical line intermediate the ends of the berths and are buttoned at 616 (Fig. 19). The segments are slit horizontally adjacent to the intermediate berth to form flaps 617, which project below the plane of the intermediate berth at 618. The lower portions 619 and 620 of segments 611 and 612, respectively, across their top edges where the flaps 617 are cut away, are provided with straps 621 secured to the lower portions of the segments 611 and 612 and wrapped around rod 243, extending lengthwise along the outer edge of the intermediate berth. Straps 621 are buttoned in place at 622 (Fig. 20).

The curtain segments 611 and 612 across the area where they are not slit are fastened to rod 243 by means of straps 623 secured to the inner face of each curtain segment and buttoned to the curtain at 624 (Fig. 21). The separations between the various curtain segments for the upper, intermediate, and lower berths substantially midway between the ends of the berths provide means for giving access to and from the berths.

Referring to Fig. 2, a shoe pocket 625 is fastened to the outside of upper curtain segment 595; a second shoe pocket 626 is fastened to the upper portion of segment 612 of the curtain; and a third shoe bag 627 is secured to the lower portion 620 of curtain segment 611. These shoe pockets 625, 626, and 627 are intended for use of the occupant of the upper, intermediate, and lower berths, respectively. When these occupants have retired to their respective berths, they may place their shoes in the pockets intended for their use, conveniently reached from the berth.

Extending downwardly from the upper berth curtain segment 597 are a pair of clothes hangers 628 and 629, secured to the curtain segment 598 on the inside face thereof by suitable straps. One of these hangers is intended for the use of the occupant of the upper berth, and the other for the occupant of the intermediate berth. To the segment 611 of the lower berth curtain 596 is a clothes hanger 631 attached to the outer face of the berth segment adjacent to the intermediate berth by a suitable strap. This latter clothes hanger is intended for the use of the occupant of the lower berth.

SUMMARY

Increased revenue earning power for sleeping cars results from the present invention. Each passenger is provided with adequate room and comforts comparable to those furnished in many of the higher priced room accommodations. During the daytime, he can adjust his seat to suit his own requirements, and at night he is provided with a roomy, comfortable bed. All of these comforts are available to the travelling public at a cost only slightly greater than the normal day coach fare. This is made possible by increasing the number of passengers accommodated over and above prior sleeping cars, and it is the arrangement of the berths that is responsible for this increase.

The berths are easy to handle, requiring only a fraction of the time previously needed to prepare standard berths for night use. During the daytime, the intermediate and upper berths are entirely out of the way of the room occupants.

We claim:

1. In a passenger vehicle, a room, a lower berth, an intermediate berth, and an upper berth all arranged in parallel, overlying relationship adjacent to one of the room walls, means for converting the lower berth independently of the other

berths into a seat with a seat portion and a back, the upper berth being fixed in a horizontal position in the upper region of the room, and the intermediate berth being foldable to inoperative position against the underneath face of the upper berth and comprising a pan having its open side facing upwardly when the intermediate berth is against the upper berth, means for pivoting the pan downwardly about a horizontal axis and 10 against the adjacent room wall, an intermediate berth member in the pan, and means for pivoting the intermediate berth member outwardly to horizontal, operative position from the pan about a horizontal axis to a position substantially at right angles to the pan.

2. In a vehicle comprising a car, a lower berth placed in the lower region of the car, an upper berth in the upper region of the car parallel to and overlying the lower berth and permanently 15 fixed in place, an intermediate berth pan closed against the underneath surface of the upper berth when not in use, means for pivoting the intermediate berth pan downwardly about an axis extending lengthwise to the berth and positioned 20 adjacent to the rear edge of the berth, a berth pivotally mounted adjacent to the forward edge of the berth pan about an axis extending lengthwise to the berth and foldable into the pan, means for fastening the berth pan in a position substantially at right angles to the upper berth when the pan is lowered for operative use, and means for fastening the intermediate berth in a horizontal position substantially midway between the upper 25 and the lower berths when said intermediate 30 berth is open for night use.

3. In a passenger vehicle, a lower berth, an intermediate berth, and an upper berth arranged in parallel, overlying relationship, a curtain support above the upper berth and substantially coextensive with the length of the berth, a curtain support adjacent to the edge of the upper berth substantially coextensive therewith and lying in a vertical plane through the upper curtain support, a curtain arrangement in the vertical plane 40 closing one side of all berths and comprising an upper curtain suspended from the upper curtain support and extending below the upper berth, a lower curtain suspended from the curtain support adjacent to the upper berth and extending below the lower berth, the upper curtain being open vertically for the major portion of its height from the upper berth to the curtain support above the upper berth, means for securing the upper curtain across a portion of its lower edge to the edge of the upper berth, the lower curtain being open vertically for the major distance from the bottom thereof to its support, means for fastening a portion of the lower curtain to the edge of the intermediate berth, means for closing the vertical 45 opening in the upper curtain, and means for closing the vertical opening in the lower curtain.

4. In a railway car, a room, a berth disposed in the upper region of the room, a second berth disposed below and substantially entirely within the vertical projection of the first berth, a support for the second berth pivotally mounted closely adjacent to the underneath face of the upper berth and adapted to move from a lowered, substantially vertical position below the upper berth 50 to a substantially horizontal position directly beneath the lower face of the upper berth, the second berth being pivotally mounted along one of its side edges to the support adjacent to the edge thereof most remote from the first mentioned

pivot connection, the second berth thereby being movable about the axis of the last mentioned pivot connection to a substantially vertical position on the support, and then together with the support being movable about the axis of the first mentioned pivot to a horizontal position directly beneath the underneath face of the upper berth, the second berth having a protective casing disposed around it when the berth is in its upper inoperative position, and seating means available for use when the second berth is in its inoperative position.

5. In a passenger vehicle, a room, a lower berth, an intermediate berth, and an upper berth all arranged in parallel overlying relationship adjacent to one of the room walls, means for converting the lower berth independently of the other

berths into a seat with a seat portion and a back, the intermediate berth being foldable to an inoperative position against the underneath face of the upper berth and comprising a pan having its open side facing upwardly when the intermediate berth is against the upper berth, means for pivoting the pan downwardly about a horizontal axis and against the adjacent room wall, an intermediate berth member in the pan, and means for pivoting the intermediate berth member outwardly to horizontal operative position from the pan about a horizontal axis to a position substantially at right angles to the pan.

CERTIFICATE OF CORRECTION.

Patent No. 2,371,482.

March 13, 1945.

JAMES K. TULLY, ET AL.

It is hereby certified that error appears in the printed specification of the above numbered patent requiring correction as follows: Page 2, first column, line 63, for the word "for" read --from--; line 70, for "Fig. 1" read --Fig. 2--; and that the said Letters Patent should be read with this correction therein that the same may conform to the record of the case in the Patent Office.

Signed and sealed this 26th day of June, A. D. 1945.

Leslie Frazer
Acting Commissioner of Patents.
